STOP ACTUATING MECHANISM FOR BRAIDING MACHINES

Frank Murray, Reading, Pa., assignor to The Narrow Fabric Co., West Reading, Pa., a corporation of Pennsylvania

Application March 1, 1932. Serial No. 595,978

9 Claims. (Cl. 96—19)

My invention relates to braiding machines and particularly to devices for actuating stopping mechanism therefor in the event of breaking of a thread guided to the braiding point for incorporation in the braid.

5 Heretofore, it has been customary to provide each travelling thread-carrier of a braiding machine with a stop actuating device, such as a thread supported slide, for causing stopping of the braiding machine on breakage of the related braid-10 thread.

In cases where a core, such as an elastic thread, is incorporated in the braid it has also been customary to provide each carrier with an additional stop actuating device, such as a slidable and/or rotatable hub, each carrier supported hub being operative on breaking of any core thread to cause stopping of the machine. The provision of two devices on each carrier for actuating the 20 stopping mechanism obviously adds to the complexity of the machine and increases the cost of equipping it for automatic stopping on breakage either of any braiding thread or any core thread.

A feature of my invention is the provision of 25 a single stopping mechanism actuating device on each carrier.

A second feature is the provision of a single stop mechanism actuator on each carrier which is responsive to breaking of the related braiding 30 thread and also to breaking of any core thread for causing stopping of the machine.

In carrying out my invention I provide each carrier with a standard serving as a guide for a thread supported slide. The actuator for the 35 operating lever of the stopping mechanism is mounted on the standard as a separate slidable member and is connected to the thread supported slide by a releasable connecting member. The connecting member is pivotally mounted on the 40 stop actuator and normally engages the thread supported slide so that both are suspended from the braiding thread. The connecting member has portions adapted to contact a projecting portion of a member normally supported by a 45 core thread so as to be operated for disconnecting the stop actuator from the braiding thread supported slide to permit the actuator to independently drop into position for causing stopping of the machine on breakage of a core thread.

50 In the drawings:

Figure 1 is a front elevation, partly in section, of part of a braiding machine and shows a travelling thread-carrier provided with a device for actuating stopping mechanism on break-55 age of a core thread or a braiding thread;

Figure 2 is a side elevation, partly broken away, of a carrier showing the stop actuator thereof positioned to cause stopping of the braiding machine as a result of breakage of a core thread;

Figure 3 is a side elevation and shows my stop 60 actuating device positioned to cause stopping of the braiding machine as a result of breakage of a braiding thread;

Figure 4 is a view on the line 4—4 of Fig. 1, and shows the stop mechanism actuator about 65 to be disconnected from the slide suspended from the braiding thread for causing stopping of the machine as a result of breakage of a core thread; and

Figure 5 is a sectional view on the line 5—5 70 of Fig. 2 and shows the relation of the stop actuator to an operating lever for the stopping mechanism.

Referring to the drawings, the numeral 10 designates one of the numerous travelling thread-75 carriers provided in a braiding machine. Carrier 10 has a base comprising plates 11 and 12 spaced by a member 13 which cooperates with the usual sinuous grooves 14 in the machine bed 15 for guiding the carrier in its braiding movement. A spindle 16 extends from plate 11 and supports a spool 17 from which a braiding thread 18 extends through thread guides 20, 21, 22 and 23 to the braiding point.

The thread guides 20 and 22 are mounted on 85 a standard 24 carried by plate 11 and the guide 21 is formed in a slide member 25 guided on standard 24 and normally supported in raised position thereon by thread 18 extending between guides 20 and 22 through guide 21. Member 25 in turn 90 supports a stop actuating member 26, also slidably mounted on standard 24, through the engagement of the hook portion 27 of a releasable connecting member 28 carried by member 26 with lugs or other projections 30 on member 25. 95

Stop member 26 has wings 31 projecting beyond the sides of standard 24 and spindle 16 and adapted to be positioned in the plane of a lever 32 for engaging and actuating the latter as carrier 10 in traversing groove 14 passes the point 100 at which the lever is mounted on bed 15.

Lever 32 on actuation by member 26 is adapted to operate any desirable form of stop mechanism such as is usually provided for stopping braiding machines. As shown lever 32 is fixed 105 to a stub shaft 33 journaled in bed plate 15 and is operatively connected through members 34, 35, etc. to set the stop mechanism in operation. It is to be understood that a number of levers 32 are provided at various points on bed plate 15, as 110

usual, in order to avoid undue delay in stopping the braiding machine.

A standard 36 fixed on bed 15 between sinuous grooves 14 supports a pulley 37 which guides an elastic thread 38, or other core to be incorporated in the braid, from a suitably located supply source to the braiding point. Standard 36 has a bracket 40 and a hollow base portion 41 which form guides for a member 42 having a loop 43 by which it is suspended from thread 38. Member 42 is formed with a projection 44 adapted to be dropped into the path of the member 28 moving with carrier 10. On breakage of core thread 38 the projection 44 engages and operates member 28, as a carrier passes the point at which a core thread has broken, to disconnect stop actuating member 26 from member 25 through which it is suspended from braiding thread 18 so that member 26 becomes positioned for engaging and operating a lever 32 to stop the braiding machine.

Referring particularly to Figures 1, 4 and 5, member 28 comprises an irregularly but symmetrically bent wire formed with looped portions 45 by which it is pivotally mounted on stop member 26. The wire member 28 is bent to provide the hook portion 27 for supporting member 26 on member 25 and also to provide portions 46 extending at each side of spindle 15 and standard 24 for engagement with the projecting portion 44 of the core thread supporting member 42.

It will be apparent that a stop member 26 functions to cause stopping of the braiding machine on breakage of either a braiding thread 18 or a core thread 38. On breakage of a braiding thread 18 the members 25 and 26 are no longer supported thereby and both move downwardly on standard 24 to position member 26 for actuating stop lever 32, as indicated in Figure 3. On breakage of a core thread 38 the member 42 is no longer supported and becomes positioned, as indicated in Figures 1 and 4, for engagement by a portion 46 of connecting member 28 to pivotally move the latter and thus disconnect stop member 26 from member 25 through which it is suspended from braiding thread 18. Stop member 26 then falls to position for actuating stop lever 32 as indicated in Figure 2.

After stopping of the braiding machine as a result of breaking of a braiding thread, the thread 18 is again passed through the guides 20, 21, 22 to support the stop actuating member 26 and slide 25. In the event stopping results from breakage of a core thread 38, the slide stop actuating member 26 is moved upwardly on standard and again connected to slide member 25 by the connecting member 27, 28.

What I claim is:

1. In a braiding machine having a stop member operable to actuate stopping mechanism for said machine, a travelling braiding thread carrier, a stationary, core thread guide, and members suspended from the braiding and core threads respectively; an actuator for said stop member mounted on said carrier and cooperating with said braiding thread and core thread supported members to cause stopping of the braiding machine on breakage either of the braiding thread or a core thread.

2. In a braiding machine having a stop member operable to actuate stopping mechanism for said machine, a travelling braiding thread carrier, a stationary, core thread guide, and members suspended from the braiding and core

threads respectively; a normally inoperative actuator for said stop member mounted on said carrier and movable thereon, upon release of either the braiding thread or core thread supported members by breakage of the corresponding threads, into position to actuate said stop member for causing stopping of the braiding machine.

3. In a braiding machine having a stop member operable to actuate stopping mechanism for said machine, a travelling braiding thread carrier, a stationary, core thread guide, and members suspended from the braiding and core threads respectively; an actuator for said stop member movably mounted on said carrier and supported out of operative relation to said stop member by connection to said braiding thread supported member and disconnectable therefrom by said core thread supported member on breakage of the core thread for movement into operative relation to said stop member to cause stopping of the braiding machine.

4. In a braiding machine having a stop member operable to actuate stopping mechanism for said machine, a travelling braiding thread carrier, a stationary, core thread guide, and a member suspended from the braiding thread; a movable actuator for said stop member suspended from said braiding thread and maintained thereby out of operative relation to said stop member; and a core thread supported member operable on breakage of said core thread to release said actuator from said braiding thread for movement into operative relation to said stop member for causing stopping of the braiding machine.

5. In a braiding machine having a stop member operable to actuate stopping mechanism for said machine; a braiding carrier; a core thread; and a two part actuator for said member mounted on said carrier, said actuator being operable as a whole to cause stopping of the machine on breakage of the carrier thread and one part thereof being operable to cause said stopping on breakage of a core thread.

6. In a braiding machine having a stop member operable to actuate stopping mechanism for said machine; a braiding carrier; a core thread; a two part actuator for said member mounted on said carrier, said actuator being operable as a whole to cause stopping of the machine on breakage of the carrier thread; and a latch connecting the parts of said actuator and releasable on breakage of said core thread to permit one part of said actuator to actuate said stop member for causing stopping of the braiding machine.

7. In a braiding machine having a stop member operable to actuate stopping mechanism for said machine a stationary, core thread guide, and a travelling braiding thread carrier; a standard on said carrier; a slide suspended from the braiding thread and guided on said standard; an actuator for said stop member mounted on said standard; means operatively connecting said slide to said actuator for maintaining the latter out of operative relation to said stop member; and a member suspended from the core thread and operable on release thereof by breakage of the core thread to disconnect said actuator from said slide to permit it to move into position for actuating said stop member to cause stopping of the braiding machine.

8. In a braiding machine having a lever operable to actuate stopping mechanism for said machine, a travelling braiding thread carrier, and a stationary, core thread guide; a standard on

said carrier; a slide suspended from the braiding thread and guided on said standard; an actuator for said lever slidably mounted on said standard; releasable means connecting said actuator to said slide to support said actuator out of operative relation to said lever; and a member freely mounted in said core thread guide and suspended from the core thread for engaging said connecting means on breakage of said core thread to disconnect said actuator from said slide to permit said actuator to move on said standard into position for actuating said lever to cause stopping of the braiding machine.

9. In a braiding machine having a stop member operable to actuate stopping mechanism therefor, a braiding thread carrier, and a core thread guide; an actuator for said stop member mounted on said carrier; and members controlled by the braiding and core threads respectively for selectively operating said actuator to cause the latter to actuate said stopping member to effect stopping of the machine upon breakage of either the braiding thread or a core thread.

FRANK MURRAY.
